UNITED STATES PATENT OFFICE.

FREDERICK C. ROCKWELL, OF HARTFORD, CONNECTICUT.

DESIGN FOR A HANDLE-BAR FOR BICYCLES.

SPECIFICATION forming part of Design No. 25,953, dated August 18, 1896.

Application filed June 16, 1896. Serial No. 595,798. Term of patent 14 years.

To all whom it may concern:

Be it known that I, FREDERICK C. ROCKWELL, a citizen of the United States, residing at Hartford, in the county of Hartford 5 and State of Connecticut, have invented and produced a certain new and original Design for Handle-Bars for Bicycles, of which the following is a specification, reference being had to the accompanying drawings, which 10 illustrate the said invention.

Figure 1 is a plan of a handle-bar for bicycles embodying my design, and Fig. 2 is a view looking at the same from one side, these 15 views being deemed necessary to illustrate my design.

The features of my design are the two swells on both sides of the middle of the bar, one swell being near each end of each half, with a curving smaller part between the two 20 swells of each half.

The axes of the parts of the bar on each side of the middle 1 extend outward in opposite directions for short distances substantially in the same straight line, which is practically horizontal. They then curve toward 25 the rear, and at the same time curve a little from horizontal until near the ends, where for short distances they extend in substantially straight lines almost directly rearward 30 and horizontal or at right angles to the direction of the axes of the straight parts each side of the middle. The contours of the bar on each side of the middle where the axes extend outward in opposite directions in sub- 35 stantially straight horizontal lines first swell outward, then inward; that is, these sections of the bar expand in size from the size of the

middle for short distances and then contract in size for similar distances until they reach the sections 2, that curve rearward. The 40 curved sections 2 on each side are of uniform size and contour, but at the straight portions that project rearward near the ends the bar again swells out for short distances and then contracts toward the ends. The swelled portions 45 3 of the bar near the middle have a somewhat long curved contour, the ends of these swelled portions curving down to the smaller parts more suddenly, whereas the swelled portions 4, that have straight axes 50 projecting almost directly toward the rear, have about the same long curved center section, but have ends 5, that taper more nearly straight from the curve of the swelled central portions to the size of the parts 2 of the 55 bar.

A bar having outline or contour of this configuration is attractive in appearance and can be artistically finished, for some portions may be of one color and some portions of another harmonizing or contrasting color, or the finish of the swelled parts may be dead, so as not to reflect light, while the smaller parts may be highly polished to reflect light, and this of course adds to the effect and appearance of the machine to which such a bar is applied.

I claim as my invention—

The design for a handle-bar for a bicycle herein shown and described.

FREDERICK C. ROCKWELL.
